[57] **CLAIM**

The ornamental design for a two handle faucet spout cap, as shown and described.

DESCRIPTION

FIG. 1 is a top perspective view of a two handle faucet spout cap showing my new design;

FIG. 2 is a side elevational view, all other sides being a mirror image thereof;

FIG. 3 is a top plan view thereof; and,

FIG. 4 is a side elevational view of a second embodiment, showing my new design, all other sides being a mirror image thereof.

The broken line showing of the faucet and handles in FIG. 1 is for purposes of illustration only and forms no part of the claimed design.

Both bottom views being plain and unornamented.
